LASTING MACHINE

Heinrich Müller and Ernst Sauer, Frankfort-on-the-Main, Germany, assignors to the firm: Maschinenfabrik Moenus Aktiengesellschaft, Frankfort-on-the-Main, Germany

Application March 2, 1938, Serial No. 193,573
In Germany March 4, 1937

20 Claims.

(Cl. 12—2)

This invention relates to a lasting machine for boots and shoes in which the margin of the upper is drawn upwardly by a gripper and laid over the edge of an insole in order there to be fastened by suitable means such as tacks or staples. It is usual in these machines, when lasting the toe part of a shoe, to slit the upper so that neighbouring parts of it can be overlapped without folding by a turning or twisting movement of the gripper. Such slitting is effected by knives or cutters forming part of a slitting device which is normally inoperative but may be thrown into operation whenever required. Usually two such knives are provided, working one at a time, and slitting the margin of the upper at one side of the gripper or the other according as the right or left hand knife is thrown into operation.

Slitting devices of the aforementioned kind have been arranged both in front of and at the rear of the gripper, as seen from the operator's stand, the latter arrangement having the advantage of providing a clear view of the work, whereas with the slitting device in front of the gripper observation is greatly obstructed. Nevertheless this arrangement has usually been given preference because it permits the knives a particularly effective slitting motion. The knives, for this purpose, were encased in a box-like structure from which they emerged with a swinging action. A slitting device, however, is known in which this box is divided into two parts arranged at the rear of the gripper one at each side of the wiper, by which arrangement the advantages of both the aforesaid types of slitting devices could largely be combined, the knives being swung outwardly by positive action and returned resiliently.

This invention is an improvement on the type of slitting device arranged at the rear of the gripper as seen from the operator's stand, and chiefly consists in the provision and the particular arrangement of parts with the object in view of obtaining an effective, reliable and amply dimensioned structure of the said kind, and one in which the entire space in front of the working parts of the machine may be left free of any parts of the slitting device so as to be fully accessible whenever required.

A further object is the elimination of any resilient control, the knives being alike positively actuated on their working stroke and on their return stroke, so that their withdrawal from the workpiece is certain, and risk of jamming or retention in the leather is obviated.

The entire slitting device is conveniently built upon a base plate positioned between the ma-

chine standard and the head of the machine; this arrangement facilitates fitting of the parts, and makes it possible to equip existing lasting machines with the new slitting device. The driving means for the slitting device include a shaft having two clutches which can be thrown into and out of gear as required by means of the gripper-controlling knee lever with which this type of machine is usually provided, and two cam discs for controlling the movements of the knife holders. A locking device prevents the knives advancing into working position both at the same time, and ensures uncoupling of the driving means when the knife last in action is no longer required, the knife being returned to its position of rest even if by inadvertence the controlling means have not fully or properly been actuated.

Other objects and improvements will appear from the following description of the accompanying drawings illustrating by way of example a slitting device according to the invention and in which

Fig. 1 is a front elevation of the base plate with the driving parts of the slitting knives partly in section,

Fig. 2 is a side elevation thereof, showing also the position of the device within the head of the machine,

Fig. 3 shows in plan the mechanism by which the knives may be put into and out of action,

Fig. 4 is a sectional elevation of this mechanism,

Fig. 5 is a side elevation of the slitting device on the left hand side of the machine,

Fig. 6 is a plan thereof,

Fig. 7 shows a modified scheme for uncoupling the slitting devices,

Fig. 8 illustrates a modified form of the operating means for the new slitting device in a part sectional elevation similar to Fig. 1,

Fig. 9 is a side view thereof,

Fig. 10 is a detail.

Arranged between the standard 1 of the lasting machine and the machine head 2, which in Fig. 1 is indicated only by some of its bearing parts, 45 is the base plate 3 upon which the whole slitting device is substantially built up. Upon the base plate, at the right and left thereof, are two brackets 4 carrying a cross shaft 5 driven by the vertical shaft 7 through a bevel wheel 6. This vertical shaft, which is driven from the main shaft 7a of the machine, normally serves to drive the tacking apparatus of the machine; for the purpose of driving the slitting device it has been extended downwardly and bears, upon this exten- 55

sion, a bevel wheel 8 meshing with the bevel wheel 6 on shaft 5.

Loose upon the shaft 5, or on the bushing 13 surrounding it, adjacent the brackets 4, are two control discs 9 and 10, in each of which are cam tracks 11 and 12. The hub of each disc is drilled at 14 to receive a clutch pin 15 on a clutch 16 fast upon the shaft 5. The clutches can slide along the shaft 5; they are connected by a rod 18 screwed into the end plates 17, and are shifted by a control slide 19, carrying a fork 20 which engages between the right hand clutch 16 and its end plate 17.

The control slide 19 moves in a guide 21 mounted on a lateral arm 22 on the base plate 3. It is governed by two cam slides 23 and 24 (Fig. 3). The cam slide 23 can be moved forward or backward by a hand lever 25 to put the slitting device into or out of operation. In it is a triangular opening 26 in which engages a stop pin 27 on the spring-pressed slide 19. Within a bore in that slide are two similar springs 28 (Fig. 4) secured in position by threaded plugs 29. These press endwise upon two sliding bolts 30 between which is a stud 31 depending from a slide 32, also moving in the guide 21 directly above the control slide 19. In the slide 32 is a slot 33 for the passage and movement of the stop pin 27 of control slide 19, so that this pin does not convey motion from one slide to the other. In addition the slide 32 carries a follower 34 projecting into a cam slot 35 in the cam slide 24. The cam or slide 24 is connected by a yoke 36 (Fig. 2) to the bell-crank lever 37 of the gripper turning box 38. On turning the well-known (and therefore not illustrated) knee lever, the bell-crank lever 37 is swung about its pivot by rod 39, and the yoke 36 causes the cam slide 24 (Fig. 3) to share the movement, and thus bring either the part 35' or the part 35'' of the cam slot 35 into engagement with the follower 34, shifting it to right or left as the case may be. This displacement is transmitted by stud 31, bolts 30, and springs 28 to slide 19 and through the fork 20 to the clutches 16, and either the righthand control disc 10 or the lefthand disc 9 becomes connected by its clutch pin 15 to the driven shaft 5 according as the knee lever is swung to right or left.

But this shifting of slide 19 and actuation of the clutches by the cam slide 24 can take place only when the slitting device is in gear. The cam slide 23 controlled by handle 25 frees the control slide 19 only when the broad portion of its triangular opening 26 registers with the stop pin 27. In the position shown in Fig. 3 the pin 27 is confined in the apex of the triangle and no displacement of the control slide 19 is possible. But notwithstanding that the control slide is thus locked the cam slide 24 can still move when the gripper swinging device, i. e. the knee lever and bell-crank lever 37, is actuated; for the slot 33 permits movement relatively to the stop pin 27 and the springs 28 yield to permit movement of the stud 31 relatively to the stationary control slide 19.

If now, the control slide 19 being freed by the cam slide 23, one of the two slitting devices, say that on the left hand side of the machine, is put into gear by the operation of cam slide 24, movement is transmitted from the control disc 9 or 10 to the following mechanism, which is duplicated on the two sides of the machine, Figures 5 and 6 showing that on the left hand side actuated by the disc 9.

Pivoted on a bracket 40 on the base plate 3 are two cam levers 41 and 42 (Figs. 5 and 6), the

former carrying a roller 43 running in the cam track 11 and the latter a roller 44 in the cam track 12 of the control disc 9. In the free ends of the levers are sockets to receive the ball ends of adjustable connecting rods 45 and 46 respectively, these rods having ball and socket connections to a bell-crank lever 47 and a one-arm lever 48 respectively.

Another bracket 49 is bored to receive sliding bolts 50 secured to a knife guide 51 in which slides the stem 54 of a knife holder 53. Feathers 55 or the like prevent the stem 54 turning.

When the left-hand clutch 14, 15, 16 (Fig. 1) is thrown into gear by the operation of the part 35'' of the slot in cam slide 24, the control disc 9 begins to rotate with the shaft 5. The first result is that lever 42 (Fig. 5 and 6) is rocked so as through rod 46 to swing lever 48 toward the right and thereby through link 56 to advance the knife holder 53 within its guide 51 toward the right in Fig. 6. The tip of the knife moves from the position *a* to point *b*. Then the cam path 11 comes into action, and causes lever 41 to rock, and through rod 45 to turn the bell-crank lever 47 about its pivot 57, so that its free arm acting through link 58 shifts the knife guide 51 and its sliding bolts 50 inwardly. Thus while the parts 42, 46, 48 remain at rest the tip of the knife moves laterally, without simultaneous forward movement, from point *b* of its path to point *c*, cutting into the upper leather while it is held by the lasting gripper 59 in tightened condition. Next, with the parts 41, 45 and 47 at rest the knife holder 53, 54, moving in its stationary guide 51, is again advanced in a straight line by the lever 42 operating through rod 46, lever 48 and link 56, so as to cause the knife edge to move from *c* to *d* and slit the leather. The knife is then positively returned along the at first curved and then straight path *d*—*a*, to the starting position illustrated in Fig. 6.

To prevent the control discs 9 and 10 passing their initial position after uncoupling, it is advisable to provide—in addition to a spring-controlled and preferably positively actuated brake 45—*a* a spring catch 61 adapted to engage in a notch of the cam disc. This spring catch may be mounted on the wiper carriage (not shown) so that in case the cam disc should not fully reach its end position it would be engaged by the catch 61 in the next return movement of the wiper and its rotation completed.

To prevent the knife on one side of the slitting device being advanced while that on the other side is in operation and to prevent the knife last in operation remaining in its forward position through incomplete disengagement of the coupling, which might lead to damage, a locking device is provided which makes it impossible to shift one knife until the other has been returned to its position of rest, and the same device also separates the clutch members 14, 15 if they have remained in engagement owing to an incomplete movement of the knee lever. This device, in the example illustrated, consists of a flat bar 62 which is connected to the rearwardly extending arm 36' of the yoke 36 and which, therefore, shares the movements of the yoke (Figs. 1 and 2). The bar 62 slides in a small bracket 63 fixed to the machine frame, and in this bracket there is also a bearing 64 for a cam lever 65 which has a roller 66 pressed on a cam 67 by the spring 68. At its free end the lever 65 carries a locking plate 69 co-operating with a locking pin 80 which it can

depress into recess 81 in the stationary member 82.

In Fig. 2 the pin 80 is in its zero position in which it can be reciprocated freely over the member 82. This is the non-locking position in which the slitting device control may be actuated. If with pin 80 in this position one of the clutch pins 15 (Fig. 1) is brought into engagement with the recess 14 in the adjacent control disc, the coupling movement shifts the bar 62 and moves the pin 80 out of register with the locking plate 69, and over the non-recessed part of member 82 to right or left of the recess 81. Declutching returns it to its mid-position, and while there it is momentarily lowered by the action of the cam lever 65 on the locking plate 69 into the recess 81. If, owing to incomplete manipulation, the clutch 14, 15 has not become fully disengaged, the locking pin 80 will come to rest above one of the slanting end faces of the recess 81, upon which it will be pressed on the descent of lever 65. It is thus shifted laterally in its descent, together with the bar 62 and the parts connected to the yoke 36, 36', and so the clutch 14, 15 is disengaged.

Instead of the locking device just described, any other arrangement may of course be employed which would prevent the simultaneous operation of both slitting devices, or the sticking of one of the knives or of one of the clutches respectively. Such locking device, for example, may have the form illustrated in Fig. 7, in which the clutch pin 15 is not arranged in the clutch 16, as in the above construction, but in the control disc. A stud 71 is located in a hole 70 drilled through the disc. This stud has a rounded head 72 pressed outwardly by a spring 73 against a stationary cam plate 74 and normally projects somewhat further than the clutch pin 15, so that its other end is held engaged in a hole 75 in the clutch member 16. When zero position is reached in the rotation of the control disc the stud 71 springs into a cavity 76 in the plate 74, and is thus withdrawn from the hole 75. Thus in each rotation the engagement of the clutch member 16 with the control disc is only interrupted exactly in zero position even if for any reason the clutch pin 15 should have become disengaged prematurely from the recess in the member 16. When the disc again begins to turn the head 72 runs up an inclined surface on the cam plate 74 and is thus re-engaged in the hole 75. This arrangement has the advantage of being particularly simple in construction. It eliminates a separate control and in contradistinction to the aforescribed locking device it can be mounted upon the base plate 3 together with the parts controlling the knife movements.

The modification of the operating device shown in Figs. 8 and 9 omits the hollow shaft 5 and the pin clutches 15. These parts are replaced by an ordinary shaft 105 and a fixed clutch member 116 at each end of the said shaft cooperating with loose clutch members 114 upon which the control discs 9 and 10 are arranged. Coupling between these parts is effected by means of a slidable latch 115 in the loose member 114 and a shifter 117 on the fast member 116. The said latch has the shape shown in Figs. 9 and 10 comprising a reduced portion 118 and it is pressed upon by a spring 119 leaning against an abutment 120 and tending to push the latch outwardly with its body portion in the way of the shifter 117 as illustrated in Fig. 10A. During the normal run of the machine the slitting device is not in operation so

that shaft 105 and its clutch members 116 and 114 are at rest.

Throwing the slitting device into actuating position is effected by means of a hand lever 121. In Fig. 8 this hand lever is shown in a position in which it would allow the aforementioned knee lever (not shown) to operate one of the slitting devices either on the right or on the left hand side of the machine by the up or down movement of the knee lever rod 39. It will be seen that similar to the cam slide 23 and stop pin 27 in Fig. 3 a slotted member is arranged in the shape of a bell crank lever 122. The horizontal arm of said bell crank lever has a substantially triangular slot 123, while the lower vertical arm is connected to a similar arm 124 on the other side of the machine by a rod 125. Hand lever 121 turns on a pivot 126 and is provided with an arm 127 on which is a pin 128 adapted, by the movement of the hand lever, to be positioned within the pointed end of the triangular slot 123 or in the base of the triangle as shown in Fig. 8. In the former case the bell crank lever 122 is prevented from rocking and any movement up or down of the knee lever rod 39 will be taken up by the springs 130 being compressed as by the pins 130 sliding in casings 131 which are fastened to the knee lever rod 39.

Turning of the hand lever 121 into the position of Fig. 8 places pin 128 in the broad end of slot 123 as shown. In this position the pins 130, on the up or down movement of the knee lever rod 39, will cause the horizontal arm of bell crank lever 122 to rock. Presuming rod 39 to be moved in an upward direction as indicated by the arrow r, in this case the lower pin 130 turns the horizontal arm of the bell crank lever upward and thereby rocks its pivot pin 132 so as to cause a lever 133 to tilt inwardly toward the left. This lever is provided with a guide 134 in which moves a slide 135, said slide being normally kept in a raised position by a spring arranged between its lower end and an abutment on the lever 133. Tilting of the said lever 133 brings the slide 135 into the path of the constantly rotating depresser 136 on the clutch 116 which depresses the slide against the action of its spring and causes a projection or nose 137 to depress a trip lever 138 against the action of its spring 139 and to thereby tip a blade 140 about its pivot 141 out of the way of the latch 115, 118 (Fig. 10A). Normally the said blade has its position underneath the latch and keeps the latter pushed back within the loose clutch member 114, as shown in Fig. 10B, so that the constantly rotating shifter 117 of the fast clutch member 116 passes underneath its shoulder 115a without touching it.

The blade 135 having been tipped in the manner just described, latch 115 is pushed by its spring 119 into the position shown in Fig. 10A in which the shifter 117 is able to abut with the latch and to cause same to join its rotation and thus also to rotate the loose clutch member 114 with the control disc 10, which now moves the cam levers 41 and 42 (Figs. 5 and 6) to operate the slitting device in the manner already described.

So long as the knee lever rod 39 is kept in its upper position the slitting device on the right hand side of the machine will continue in its operation and a slit will be cut into the upper at each revolution of shaft 105. As soon, however, as rod 39 is returned into its neutral position the various parts reassume their non-working positions according to Fig. 8, in which lever 133

is swung back with its slide 135 out of the way of the depresser 136, so that the trip lever 138 is released and 140 returned by spring 139 into its vertical position in which it is engaged by the step 118 of latch 115 (Fig. 9) so that the latter is raised with its edge 115a out of the path of the shifter 117. No slitting operation is now being performed.

If the operation of the left hand slitting device is required rod 39 is moved by the knee lever in a downward direction as indicated by the arrow 1. This causes bell crank lever 122 to swing its depending arm towards the left and by means of the connecting rod 125 to tilt lever 133a inwardly over the trigger 138 whereupon the operation just described will now be performed by the devices on the left hand side of the machine.

What we claim is:

1. In a lasting machine having a gripper and slitting knives at the rear of the gripper one at each side of it, means for operating the knives comprising a driving member at right angles to the main shaft of the machine, control members arranged upon said driving member, a clutch to connect said control members one at a time to said driving member, and means arranged on the two sides of the machine standard for transmitting motion from said control members to the knives.

2. In a lasting machine having a gripper and slitting knives at the rear of the gripper one at each side of it, means for operating the knives comprising a lay shaft extending from right to left in the machine, control members arranged upon said lay shaft, a clutch to connect said control members one at a time to said lay shaft, and means arranged on the two sides of the machine standard for transmitting motion from said control members to the knives.

3. In a lasting machine having a gripper and slitting knives at the rear of the gripper one at each side of it, means for operating the knives comprising a lay shaft extending from right to left in the machine as seen from the operator's stand, a clutch member near each end of said lay shaft, a control member adjacent each of said clutches, means to operate said clutches to connect said control members one at a time to the lay shaft, and means arranged on the two sides of the machine standard for transmitting motion from said control members to the knives.

4. In a lasting machine having a gripper and slitting knives at the rear of the gripper one at each side of it, means for operating the knives comprising a lay shaft extending from right to left in the machine as seen from the operator's stand, a clutch member near each end of said lay shaft, a control member adjacent each of said clutches, a movable clutch rod arranged substantially parallel to said lay shaft and connecting the clutch operating means at one end of the lay shaft with those at the other end thereof, means to move said clutch rod so as to operate one clutch at a time, and means arranged on the two sides of the machine standard for transmitting motion from said control members to the knives.

5. In a lasting machine having a gripper and slitting knives operating from the rear of the gripper, one at each side thereof, towards the front of the machine, a lay shaft, a clutch at each end of said lay shaft rotating therewith, a cam adjacent each of said clutches and loosely rotatable on said lay shaft, means to operate said

clutches, to connect said cams, one at a time, to the lay shaft, a clutch rod arranged substantially parallel to the lay shaft and connecting the clutch operating means for the two clutches with one another, and means arranged on the two sides of the machine standard for transmitting motion from said cams to the knives.

6. In a lasting machine having a gripper and slitting knives at the rear of the gripper one at each side of it and a main shaft for imparting motion to the instrumentalities of the machine, means for operating the slitting knives comprising a lay shaft arranged below the main shaft, a gear between said main shaft and said lay shaft for imparting constant positive rotation to said lay shaft, a clutch member connected to each end of said lay shaft, control members adjacent said clutch members and loosely rotatable on the lay shaft, means to connect said clutches one at a time to said control members, and means arranged on the two sides of the machine standard for transmitting motion from said control members to the knives.

7. In a lasting machine having a gripper and slitting knives at the rear of the gripper one at each side of it and a main shaft for imparting motion to the instrumentalities of the machine, means for operating the slitting knives comprising a lay shaft arranged below the main shaft at substantially right angles thereto, a vertical shaft between the main shaft and the lay shaft, gear wheels to derive motion from the main shaft to the vertical shaft and another set of gear wheels to transmit said motion positively to the lay shaft, a clutch at each end of the lay shaft rotatable therewith, a cam adjacent thereto and arranged loosely upon said lay shaft, means to connect said clutches one at a time to said cams, and means arranged on the two sides of the machine standard for transmitting motion from said cams to the knives.

8. In a lasting machine having a gripper and slitting knives at the rear of the gripper one at each side of it, means for operating the knives comprising a lay shaft, a clutch and a control member at each end of said lay shaft, means to connect said clutches one at a time to said control members, means arranged on the two sides of the machine standard for transmitting motion from said control members to the knives, and a base plate fitted between the machine standard and the head of the machine provided with bearings and supporting surfaces for carrying substantially all the said knife operating means.

9. In a lasting machine having a gripper and slitting knives at the rear of the gripper one at each side of it, means for operating the knives comprising a constantly driven shaft, a clutch and a control member at approximately each end of said shaft, manually operable means to connect said control members one at a time to said clutches and the shaft, a knife selecting device, means arranged on the two sides of the machine standard for transmitting motion from said control members to the knives, and automatically operating means for securing the return of the parts into zero position if the return of the said selecting device is incompletely effected.

10. In a lasting machine having a gripper and slitting knives at the rear of the gripper one at each side of it, a constantly rotatable lay shaft, a fast clutch member fitted to each end of said lay shaft and a loose clutch member adjacent thereto, a control member fixed to each of said loose clutch

- members, a spring-controlled latch in each of said loose members and a shifting member on said fast clutch members co-operating with said latch, means for normally withholding said latch out of the path of said shifter, means for rendering said withholding means inoperative, and means arranged on the two sides of the machine standard for transmitting motion from said control members to the knives.
- 5 11. In a lasting machine having a gripper and slitting knives at the rear of the gripper one at each side of it, a constantly rotating lay shaft extending from right to left of the machine, a fast clutch member fitted to each end of said lay shaft and having a shifting member protruding from its circumference, a loose clutch member on the lay shaft adjacent said fast member and having a spring controlled latch slidable within it, said latch being provided with a set-off portion, a movable member co-acting with said set-off portion for normally holding said latch within said loose clutch member, manually operable means for temporarily withdrawing said movable member so as to release said latch and permitting it to protrude 15 with its body portion into the circular path of the said shifting member, a cam fixed to said loose clutch member, and means arranged on the two sides of the machine standard for transmitting motion from said cams to the knives.
- 20 12. In a lasting machine having a gripper and slitting knives at the rear of the gripper one at each side of it, a constantly rotating lay shaft extending from right to left of the machine, a fast clutch member fitted to each end of said lay shaft and having a shifting member protruding from its circumference, a loose clutch member on the lay shaft adjacent said fast member and having a spring controlled latch slidable within it, said latch being provided with a set-off portion, a movable member co-acting with said set-off portion for normally holding said latch within said loose clutch member, a manually operated rocking lever, a spring controlled slide within a guide of said rocking lever protruding therefrom and having a projection, a trip lever in connection with said movable member and positioned for co-operation with said projection, a depresser on and constantly rotating with said fast clutch member and adapted to depress said slide in said rocking lever, when same is rocked towards the said trip lever so as to remove said movable member from contact with said latch, a cam fixed to the said loose clutch member, and means arranged on the two sides of the machine standard for transmitting motion 25 from said cams to the knives.
- 30 13. In a lasting machine having a gripper and slitting knives at the rear of the gripper one at each side of it, means for operating the knives comprising in combination, a shaft, means to rotate said shaft, a fast clutch member and a loose clutch member at each end of said shaft, manually controllable means to connect said fast and loose clutch members at one side of said shaft, a cam having two cam grooves on each of said loose clutch members, a connection for connecting said manually controllable means of one side to those of the other side of the shaft and comprising a lever having a triangular slot, a knife selecting device having two spring controlled pins for locking the said lever, a hand lever and a stop pin on said hand lever adapted to be moved into the apex of said triangular slot for locking said manually operable means against movement, and means arranged at the two sides of the machine standard for transmitting motion from said cams to the knives.
- 35 14. In a lasting machine having a gripper and slitting knives at the rear of the gripper one at each side of it, means for operating the knives comprising a lay shaft, a clutch and a control member at each end of said lay shaft, means to connect said clutches one at a time to said control members, means arranged on the two sides of the machine standard for transmitting motion from said control members to the knives, a base plate fitted between the machine standard and the head of the machine, bearings on said base plate for carrying said lay shaft, cam levers and knife holders at each side of said base plate, bracket arms extending from said base plate for movably supporting said cam levers and knife holders, and connecting means between said cam levers and knife holders for transmitting motion from the former to the latter.
- 40 15. In a lasting machine having a gripper and slitting knives at the rear of the gripper one at each side of it, knife holders capable of lengthwise sliding motion, knife holder carriers capable of sliding motion crosswise thereto, means for imparting motion to said knife holders and knife holder carriers comprising a constantly driven shaft, clutch members and cams at approximately the ends of said shaft, and manually operable means for connecting said cams one at a time to said shaft.
- 45 16. In a lasting machine having a gripper and slitting knives at the rear of the gripper one at each side of it, knife holders capable of lengthwise sliding motion, knife holder carriers capable of sliding motion crosswise thereto, means for imparting motion to said knife holders and knife holder carriers comprising a constantly driven shaft, clutch members and cams at approximately the ends of said shaft, cam levers and levers for moving said knife holders and knife holder carriers, manually adjustable connections between the said levers, and manually operable means for connecting said cams one at a time to the said shaft.
- 50 17. In a lasting machine having a gripper and slitting knives at the rear of the gripper one at each side of it, knife holders capable of lengthwise sliding motion, knife holder carriers capable of sliding motion crosswise thereto, means for imparting motion to said knife holders and knife holder carriers comprising a constantly driven shaft, clutch members and cams at approximately the ends of said shaft, cam levers and levers for moving said knife holders and knife holder carriers, oscillating levers pivoted to the knife holders and the knife holder carriers, and manually adjustable connecting rods between said cam levers and said oscillating levers for transmitting motion from the former to the latter.
- 55 18. In a lasting machine having a gripper and slitting knives at the rear of the gripper one at each side of it, a base plate arranged between the machine standard and the head of the machine and entirely independent of other structures of the lasting machine, bearings on the said base plate, a constantly driven shaft journaled in the said bearings in a position to extend from right to left of the machine, a clutch and a cam at approximately each end of said shaft, two bracket arms extending from the base plate on each side of the machine standard, one of said arms serving to support cam levers and the other arm to carry a guide for slidably supporting the knife holder and knife holder carrier, and adjustable 60

- connections between said cam levers and the slitting knife operating means.
19. In a lasting machine having a gripper and slitting knives at the rear of the gripper one at each side of it, knife holders capable of lengthwise sliding motion, knife holder carriers capable of sliding motion crosswise thereto, means for imparting motion to said knife holders and knife holder carriers comprising a constantly driven shaft, clutch members and cams at approximately the ends of said shaft, two cam levers on each side of the machine standard in connection with each of the cams, a connection between one of said cam levers and said knife holder for imparting lengthwise sliding motion to it, and a connection between the other of said cam levers and said knife holder carrier for imparting crosswise motion thereto.
20. In a lasting machine having a gripper and slitting knives at the rear of the gripper one at each side of it, a knife holder for each knife capable of lengthwise sliding motion, a knife holder carrier forming a guide for said knife holder and provided with slidable supporting members for movement crosswise to the movement of the knife holder, a fixed guide for slidably supporting said knife holder carrier, means for imparting motion to said knife holder and knife holder carrier comprising a constantly driven shaft, control members and clutch members on said shaft, and manual clutch operating means for connecting said control members one at a time to said shaft.
